ADJUSTABLE EARTH IMPLEMENT

Chester A. Winters, Lynnville, Iowa

Application January 20, 1936, Serial No. 59,864

5 Claims. (Cl. 97—59)

The principal object of my invention is to provide a cultivating device that permits the earth engaging element to be easily and quickly adjusted both as to height and angle of attack.

5 A further object of my invention is to provide a manually operated cultivating device that may be adjusted to conform to the height characteristics of the user.

A still further object of this invention is to 10 provide an earth conditioning implement that is economical in manufacture and durable in use.

These and other objects will be apparent to those skilled in the art.

15 My invention consists in the construction, arrangement and combination of the various parts of the device, whereby the objects contemplated are attained as hereinafter more fully set forth, pointed out in my claims and illustrated in the accompanying drawing, in which:

20 Fig. 1 is a side view of my device ready for use with dotted lines showing the adjustable features.

Fig. 2 is a top plan view of the device.

25 Fig. 3 is an enlarged view of a portion of my device taken on line 3—3 of Fig. 2, and more fully illustrating the construction of the adjustable locking mechanism.

Fig. 4 is an enlarged view of the left side of the 30 adjustable locking portion of the device with sections cut away to more fully illustrate the construction of the device.

The chief objections to ordinary hand cultivators are that their shovels are not readily adjustable in height relative to the handles and are not readily adjustable in angle of attack 35 relative to the ground to be conditioned. While my invention may be applied to large riding cultivators and/or motorized or otherwise drawn cultivators, it is particularly adapted to the small manually operated cultivators used for garden work and as will hereinafter be appreciated, overcome objections now found in ordinary hand cultivators.

Referring to the drawing, I have used the 40 numeral 10 to designate the ordinary front supporting wheel of such devices. The numerals 11 and 12 designate the two rearwardly and upwardly extending bar members, which together, form the frame of the device. The wheel 10 is positioned between the forward end portions of the two bars 11 and 12. The wheel 10 is rotatably positioned between these two bars by the bolt 13 which extends through the forward ends of the bars 11 and 12 and through the hub of the wheel 10. The numeral 14 designates a 45 straight portion in the bar 11 just back of the

wheel 10. The numeral 15 designates a similar straight portion in the bar 12 just back of the wheel 10. These two portions 14 and 15 are spaced apart from each other and are directly opposite from each other, as shown in Fig. 2. 5 From the portions 14 and 15 the bars 11 and 12 extend rearwardly, upwardly, and outwardly, eventually terminating in the two spaced apart curved handle portions 16 and 17.

The numeral 18 designates a brace bar extending between the bars 11 and 12 and positioned just forwardly of their handle portions 16 and 17. The numeral 19 designates a strengthening block on the outer side of the portion 14. The numeral 20 designates a similar strengthening block on the outer side of the portion 15. The numerals 21 and 22 designate two bolts each extending through the portions 14 and 15 and blocks 19 and 20. These two bolts 21 and 22 are spaced apart from each other, as shown in Fig. 1. 20 The numeral 23 designates an arm extending rearwardly along the left side of the wheel 10 and having its forward end portion pivoted on the bolt 13. The numeral 24 designates a similar arm extending along the right side of the 25 wheel 10 and having its forward end pivoted on the bolt 13. These two arms 23 and 24 are pivoted on the bolt 13 inside of the bars 11 and 12, as shown in Fig. 2, and are joined together at their rear end portions back of the wheel 10. 30 The numeral 25 designates a plurality of spaced apart horizontally arranged holes extending through the rear end portions of the arms 23 and 24. The numerals 26 and 27 designate two 35 posts having their lengths substantially parallel with each other and loosely extending between the two portions 14 and 15 and between the bolts 21 and 22, as shown in Fig. 3. These two posts are secured to each other by any suitable means and extend on each side of the rear end 40 portions of the arms 23 and 24, respectively. The numeral 28 designates a bolt selectively extending through any one of the holes 25 and through the two posts 26 and 27 for pivotally 45 securing the posts 26 and 27 to the arms 23 and 24 and also for holding the two rear ends of the arms 23 and 24 together. The upper end portions of the posts 26 and 27 are each bent outwardly and away from each other to form a 50 handle portion 29, as shown in Fig. 3.

The numeral 30 designates a lever bar having its forward end located between the portions 14 and 15 and pivoted around the bolt 21. This lever bar has its length extending along the 55 right side of the post 27 and terminates into a

handle portion 31 to the rear of the portions 15 and 14 and between the bars 23 and 24, as shown in Fig. 2. The numeral 32 designates a notch in the upper marginal edge portion of the lever bar 30 capable of engaging the bolt 22 between the two portions 14 and 15 when the lever bar is manually moved upwardly to a position as shown in Fig. 4. The numeral 33 designates serrations or like on the inner side of the flat portion 14. 5 The numeral 34 designates serrations or like on the right side of the post 26 capable of engaging the serrations or like on the inner side of the portion 14. The numeral 35 designates a shovel or like earth engaging element detachably 10 secured on the lower end of the posts 26 and 27. 15

The practical operation of the device is as follows: To place the device in condition for adjustment it is merely necessary to lower the lever 30 to a position shown by dotted lines in 20 Fig. 1. With the lever in this position the posts 26 and 27 may be moved upwardly or downwardly for adjustably positioning the earth engaging element 35 relative to the frame of the device. This lowering or raising of the earth engaging element 25 relative to the bars 11 and 12 will give the desired depth the earth engaging element will cut into the ground. Obviously, the further the handle portion 29 is forced downwardly relative to the frame of the device, the deeper the element 30 35 will penetrate into the ground, and on the other hand, the higher the handle portion 29 is raised relative to the frame, the shallower the element 35 will engage the ground to be conditioned. 35

This up or down manual movement of the handle 29 will cause the arms 23 and 24 to pivot and swing both on the bolt 13 and on the bolt 28. Besides adjusting the member 35 for the desired penetration into the ground, the up and 40 down adjustment of the handle 29 will also lower or raise the rear ends or handles 16 and 17 relative to the surface of the ground, thereby making possible the elevation adjustment of the handle portions 16 and 17 to compensate for 45 operators of different heights. By moving the handle 29 forwardly or rearwardly the angle of attack of the element 35 will be adjustably obtained. From this it will be seen that when the handle 29 is moved upwardly or downwardly the 50 earth engaging element 35 will be vertically adjustably positioned relative to the surface of the ground or relative to the handles 16 and 17 and by moving the handle 29 forwardly or rearwardly the posts 26 and 27 will pivot on the bolt 28 to adjustably position the earth engaging element 35 at various angles to the vertical and closer or further away from the earth engaging portion of the wheel 10. After the earth engaging element 35 is properly positioned for the work to be 55 accomplished and for the height of the operator of the device, the handle portion 31 of the lever 39 is pulled upwardly to a position as shown in Fig. 4. As the frame of the device is made of suitable metal there is a certain amount of spring 60 or give in it and when the lever 30 is moved upwardly to a position as shown in Fig. 2, it will wedge between the flat portion 15 and the post 27, as shown in Fig. 3, thereby rigidly holding the two posts 26 and 27 between the two portions 65 14 and 15 and against accidental movement relative to the frame of the device. The members 19 and 20 and the bolts 21 and 22 permit this wedging action, but limit the spreading movement of the portions 14 and 15 beyond certain 70 degrees when the lever is moved upwardly. 75

In order that there will be no question as to the wedge holding of the posts 26 and 27 between the two portions 14 and 15 I have serrated or otherwise effected the inner side of the portion 14 and the right side of the post 26. 5

The post element of the device formed by the posts 26 and 27 may also be moved forwardly or rearwardly relative to the wheel 10 by selectively placing the bolt 28 in the various holes 25 in the bracket member which is composed of the two 10 arms 23 and 24. 10

Some changes may be made in the construction and arrangement of my improved adjustable earth implement without departing from the real spirit and purpose of my invention, and it 15 is my intention to cover by my claims any modified forms of structure or use of mechanical equivalents which may be reasonably included within their scope. 20

I claim:

1. In a device of the class described, a frame having two spaced apart bars, a means for supporting one end of said frame, a bracket element having its front end hingedly secured to said frame, a post element hingedly secured between its two ends to said bracket member and having its upper end portion loosely extending between said two bars of said frame, and a lever bar hinged at one end to said frame and capable of being manually swung to a position between said two bars of said frame for wedging said post element against movement between said two bars of said frame. 25

2. In a device of the class described, a frame having two spaced apart bars, a means for supporting one end of said frame, a bracket element having its front end hingedly secured to said frame, a post element hingedly secured between its two ends to said bracket member and having its upper end portion loosely extending between said two bars of said frame, a lever bar hinged at one end to said frame and capable of being manually swung to a position between said two bars of said frame for wedging said post element against movement between said two bars of said frame, and serrations on one of said two bars and on said post element. 35

3. In a device of the class described, a frame having two spaced apart bars, a means for supporting one end of said frame, a bracket element having one of its ends hingedly secured to said frame, a post element hingedly secured between its two ends to said bracket member and having its upper end portion loosely extending between said two bars of said frame, an earth engaging member on the lower end portion of said post element, and a lever bar hinged at one end to said frame and capable of being manually swung to a position between said two bars of said frame for wedging said post element against movement between said two bars of said frame at times. 50

4. In a device of the class described, a frame having two spaced apart bars, a wheel for supporting said frame, a bracket element hingedly secured to said frame, a post element hingedly secured between its two ends to said bracket member and having its upper end portion loosely extending between said two bars of said frame and capable of both vertical and horizontal movement relative to said two bars of said frame, an earth engaging member on the lower end of said post and a lever bar hinged at one end to said frame and capable of being manually swung to a position between said two bars of said frame 65

for wedging said post element against movement between said two bars of said frame.

5. In a device of the class described, a frame having two spaced apart bars, a means for supporting one end of said frame, a bracket element having its front end hingedly secured to said frame, a post element adjustably hingedly secured between its two ends to said bracket

member and having its upper end portion loosely extending between said two bars of said frame, and a lever bar hinged at one end to said frame and capable of being manually swung to a position between said two bars of said frame for 5 wedging said post element against movement between said two bars of said frame.
